UNITED STATES PATENT OFFICE.

MOSES OFFENBERG, OF BERLIN, GERMANY.

INCANDESCENT MANTLE.

SPECIFICATION forming part of Letters Patent No. 769,449, dated September 6, 1904.

Application filed September 22, 1902. Serial No. 124,466. (No model.)

To all whom it may concern:

Be it known that I, MOSES OFFENBERG, a subject of the King of Prussia, German Emperor, and a resident of 3 Luckauerstrasse, 5 Berlin, Kingdom of Prussia, German Empire, have invented certain new and useful Improvements in Incandescent Mantles, of which the following is an exact specification.

My invention relates to improvements in incandescent mantles; and it consists in the arrangement of a great number of small threads or loops at the surface of the webbing.

The mantle is preferably made in the following manner, though I do not restrict myself 15 to the method herein shown: A webbing is woven of the shape and form of the ordinary mantle, (marked *a* in the drawings.) In this are interwoven loops *b*, which while firmly fastened to the fabric *a* do not assist in supporting the skeleton of the mantle, but hang 20 downwardly and outwardly from the webbing *a*. The purpose of these loops *b* is not to form an additional skeleton for the mantle, but only to provide increased illuminating- 25 surface for the mantle. These loops are preferably inserted transversely in the fabric of the webbing *a* and at the points where the links of the webbing are joined, there being a series of loops from each vertical series of 30 links in the webbing.

It is found that the ordinary mantle by continual use contracts of its own weight after alternate heating and cooling, and this is one of the principal reasons of the constantly-diminishing illuminating power of the ordinary mantle. In my mantle this tendency is counteracted by the loops *b*, which having no weight to support do not contract in use, and therefore afford a constant illuminating-surface 35 during the whole life of the mantle. The effect of this arrangement of loops is practically to give a double skeleton to the mantle, one forming the inner frame and supporting the second, consisting of the interwoven loops or threads *b*. By cutting of the

projecting ends of the loops *b* as shown in Fig. 6 of the drawings a still greater illuminating-surface is obtained for my mantle. These loops must be cut before the webbing is impregnated with the incandescent salts, 50 and the roughened threads afford a greatly-enlarged illuminating-surface in the finished mantle.

My invention is shown in the accompanying drawings, in which—

Figure 1 is a view of a mantle, showing thread-loops arranged in regular distances from one another and projecting over the surface of the webbing. Fig. 2 is a vertical section of the mantle shown in Fig. 1. Figs. 3 60 and 4 are views of the webbing in an enlarged scale. Fig. 5 is a vertical section of the webbing. Fig. 6 is a modification of the webbing, showing the projecting loops cut so as to form small threads.

In the drawings, *a* is a ground-webbing of the mantle, and *b* are the loops or threads projecting over the same. By the arrangement of the threads or loops a much better effect of the mantle will be obtained, as the incandescent surface is enlarged without a greater quantity of gas being necessary. In case the projecting loops are cut so as to form projecting threads, as shown in Fig. 6, it has proved advantageous to cut the threads in 70 that way that the cutting-surface is not flat, but that the fibers of the thread are somewhat loose at the ends.

It has already been tried to attain a better effect in incandescent mantles by arranging 80 loose rings in the meshes of the webbing; but these rings are very soon torn off by the pressure of the gas, thereby destroying the incandescent surface of the mantle.

Having thus fully described the nature of 85 my said invention, what I desire to secure by Letters Patent of the United States is—

1. In an incandescent-mantle frame, the combination of a ground-webbing, loops inserted therein and outwardly extending from 90

said webbing, said loops being cut so as to leave projecting threads depending from said webbing.

2. In an incandescent-mantle frame, the combination of a webbing and of threads supported by and with their ends outwardly extending from said webbing, substantially as described and for the purpose set forth.

In testimony whereof I have signed my name to this specification in the presence of two sub- 10 scribing witnesses.

MOSES OFFENBERG.
